UNITED STATES PATENT OFFICE.

CHRISTIAN BERGSTROM, OF DENVER, COLORADO, ASSIGNOR TO THE BERGSTROM-BREWSTER MOTOR COMPANY, OF DENVER, COLORADO, A CORPORATION OF COLORADO.

ADJUSTABLE FRAMING-JOINT.

1,364,173.

Specification of Letters Patent.

Patented Jan. 4, 1921.

Application filed February 24, 1919. Serial No. 278,955.

To all whom it may concern:

Be it known that I, CHRISTIAN BERGSTROM, a citizen of the United States, residing at the city and county of Denver and State of Colorado, have invented certain new and useful Improvements in Adjustable Framing-Joints; and I do declare the following to be a full, clear, and exact description of the invention, such as will enable others

skilled in the art to which it appertains to make and use the same, reference being had to the accompanying drawings, and to the characters of reference marked thereon, which form a part of this specification.

This invention relates to joints for framing, and while it is designed primarily for bodies of trucks and the like, it is by no means limited to such use. The object of the invention is to furnish a joint which will not weaken the timbers and which permits of tightening in case the parts become loose from vibration or other causes.

Briefly, the invention comprises a shoe having spaced ears to which a joist is adapted to be bolted, the shoe being adapted to ride on a sill or other beam, and plates to be secured to the sill or beam and connected with the shoe by bolts, whereby the joists and sill will be rigidly secured together.

In the drawings:

Figure 1 is a fragmentary perspective, showing the joint in use; and

Fig. 2 is a perspective of the parts of the joint disassembled.

By means of the joint the joist A is connected to sill B, the latter in the case of a truck being suitably mounted on the chassis rail C.

The joint comprises the shoe 10 from the opposite sides and opposite ends of which ears 12 and 14 extend upwardly, these being apertured at 16 and 18, respectively, for the reception of bolts 20 by which the joist A is secured thereto, nuts 22 being tightened on the bolts 20 to maintain a fixed relation. A bearing plate 24 is mounted upon the sill B and has a transverse channel 26 in which the shoe 10 seats. The bearing plate is secured to the sill by apertures 27 and screws 28 therein.

The opposite ends of the shoe are provided on their under sides with bosses 30 having recesses 31 which receive the heads 32 of

bolts 33 which pass through the bosses 30. Plates 34 are bolted to the sill B by means of bolts 36 passing through apertures 38. The plates 34 have lateral lugs 40 apertured for the reception of the lower ends of the bolts 33, and nuts 42 are applied to the extremities of bolts 33 to draw the sill tightly against the shoe 10 and retain the parts in position.

It is evident that if the parts become loose from wear due to vibration, that tightening of the various nuts and bolts will readily restore the solidity of the joint. The diagonal positioning of the ears 12 and 14 will permit the joist being drawn toward each ear when the nuts 22 are tightened, so that the joist will take a slightly diagonal position; or, if the joist will not assume an angular position, tightening of the nuts will take up any play along the length of the bolts and hold the joist in fixed and solid relation with respect to said ears.

I claim:

1. In combination, a joist, a beam, a shoe resting upon said beam, means securing the shoe to the beam, a rigid upstanding ear at each of two diagonally opposite corners of said shoe, said joist resting upon said shoe and positioned between said ears, and two bolts having nuts, each bolt extending through one of said ears and through said joist, whereby tightening of each nut independently will take up play of said joist along the respective bolt.

2. A framing joint, comprising a shoe, ears on said shoe, said ears being positioned only at two diagonally disposed corners of said shoe, means for connecting the shoe with a beam and means on each ear for adjustably connecting the respective ears to a joist.

3. In combination, a joist, a beam, a shoe resting upon said beam, means for securing the shoe to the beam, a rigid upstanding ear at each of two diagonally opposite corners of said shoe, said joist resting upon said shoe and positioned between said ears, and adjustable means passing through said joist and connected with each ear to draw the joist toward the respective ears, whereby play may be taken up.

In testimony whereof I affix my signature. CHRISTIAN BERGSTROM.
